(57) **CLAIM**

The ornamental design for smoking pipe, as shown and described.

DESCRIPTION

FIG. 1 is a left side perspective view of a smoking pipe.

FIG. 2 is a left side, rear perspective view of the smoking pipe shown in FIG. 1.

FIG. 3 is a left side elevational view of the invention.

FIG. 4 is a right side elevational view of the invention.

FIG. 5 is a front end view of the invention.

FIG. 6 is a rear end view of the invention.

FIG. 7 is a top plan view of the invention.

FIG. 8 is a bottom plan view of the invention.

FIG. 9 is a left side perspective view of the invention similar to the view shown in FIG. 1 showing the housing moved rearward over the base, the bowl and the lighter; and, FIG. 10 is a top plan view of the invention, shown with the mouth piece rotated outward.
